UNITED STATES PATENT OFFICE

ERNST G. APPLETON, OF CHICAGO, ILLINOIS, ASSIGNOR TO ROACH-APPLETON MANUFACTURING COMPANY, OF CHICAGO, ILLINOIS, A CORPORATION OF ILLINOIS

LATH SUPPORT

Application filed October 19, 1925. Serial No. 63,244.

The present invention relates to lath supports.

In electric house wiring it is common practice to provide brackets or supports for electric fixtures which brackets or supports are secured to the joists or studding of the building. Inasmuch as electric fixtures project through the plaster, it is necessary to interfere with the laths upon said joists or studding. Said laths are commonly left with their ends free, resulting in a very unsatisfactory structure.

An object of the present invention is to provide lath supporting means which will cooperate with electric fixture supporting means and with well secured laths to secure the free ends of other laths in position.

A further object is to provide lath supporting means which will cooperate with fixture supporting means and laths, as these devices are commonly known and used, to hold the free ends of said laths firmly in position.

A further object is to provide lath supporting means for bracing the free ends of certain laths by supporting same from other laths which may be firmly secured.

A further object is to provide a lath supporting means which is efficient in operation and cheap to manufacture.

Further objects will appear as the description proceeds.

Referring to the drawings—

Figure 1 is a front elevation of the studding of a building, the laths supported thereby, an outlet box with its supporting means, and a pair of lath supporting members embodying the principles of the present invention;

Figure 2 is a rear view of part of the structure shown in Figure 1;

Figure 3 is a sectional view taken along the plane indicated by the arrows 3—3 of Figure 1; and

Figure 4 is a view in perspective of the lath supporting member shown in Figures 1 to 3.

The numerals 1—1 indicate wall studs, and the numerals 2—2 indicate laths, each of which is nailed or otherwise secured to adjacent studs. The numeral 3 indicates an out-

let box support, which support is carried by the elongated bar 4, which is secured to adjacent studs.

The outlet box support 3 is commonly of greater dimensions in a plane parallel with the broad surface of the laths 2—2 than the normal spacing between adjacent laths. According to the structure shown in Figure 1, the outlet box support 3 occupies space almost equivalent to the space occupied by two adjacent laths. In order to accommodate said outlet box supports, certain laths must be cut. Such cut laths are indicated by the numerals 5—5. The ends of said laths 5—5 adjacent to the outlet box support 3 may be spaced a considerable distance from the nearest joist or studding 1, and the present invention contemplates a simple device for supporting the free ends of said cut laths 5—5.

Referring particularly to Figure 4, the numeral 6 indicates a sheet metal member, which should be galvanized, or treated in some other manner, to prevent corrosion.

Said sheet metal member is provided midway of its length with the outstruck ears 7—7, which ears in cooperation with the base portion of the member 6 are adapted to slidably receive the bar 4.

The numerals 8—8 indicate lips which are struck out from the metal of the member 6 a distance substantially equal to or a little more than the normal thickness of builder's lath.

Said lips 8—8 have oppositely projecting end portions 9—9 adapted to hold the laths 5—5 against lateral displacement.

The numerals 10—10 indicate outstruck lips having oppositely extending end portions 11—11, the end portion 11 of each lip 10 extending in the same direction as the end portion 9 of the adjacent lip 8.

The outstruck portions of each lip 8 and the adjacent lip 10 are spaced apart a distance substantially equal to or slightly greater than ordinary builder's lath.

The end portions 11—11 of said lips 10—10 are spaced from the flat portion of the member 6 a distance equal to or slightly greater than the thickness of ordinary builder's lath.

Said lips 8—8 and 10—10 are struck out at substantially right angles to the base portion of the member 6, and the end portions 100

9—9 and 11—11 are disposed in a plane substantially parallel with the base portion of said member 6.

In use, a pair of members 6—6 will be used upon each bar 4, said bar being received between the outstruck ears 7—7 and the base portion of the member 6. The bar 4 will be nailed or otherwise secured adjacent to its extremities to adjacent studs or joists 1—1, 5 with one or two of the members 6 (depending on conditions) supported on said bar ready for the lather to do his work. The upper outstruck lip 10 with its end portion 11 will be disposed in holding relationship 10 with the upper lath 2, and the lower outstruck lip 10 with its end portion 11 will be mounted in holding relationship with the lower lath 2, said lower lath being spaced three laths below the upper lath 2. 15 The outstruck lips 8—8 with their end portions 9 will receive the free extremities of the cut laths 5—5, other portions of said cut laths 5—5 being nailed or otherwise secured to the joists or studs 1—1. 20 25 By reason of the present invention a simple structure is had which will support the ends of lath members when said ends are disposed intermediate of adjacent studs or joists. Though the described embodiment of the 30 present invention provides means having holding relationship with a bar secured to the joists, as well as means having holding engagement with laths which are secured to adjacent joists, it will be clear that, if preferred, the ears 7—7 for holding the member 6 upon the bar 4 may be omitted, support for the intermediate laths being derived solely from the laths 2—2, which are secured to both of the joists 1—1. It is preferred, 35 for practical reasons, however, to use the ears 7—7 or equivalent holding means for slidably supporting the members 6—6 upon the bar 4. If preferred, the means for holding the laths 2—2 may be omitted, support 40 for the laths which terminate intermediate of adjacent studs being derived solely from the bar 4, though such a construction would provide much less rigidity than the structure shown in the drawings. Another modification, 45 which falls within the scope of the invention is to omit the lips 10—10, the base portion of the member 6 abutting flatwise against the spaced laths 2—2. The present invention is cheap to manufacture and is effective in operation. 50 55

Though a preferred embodiment has been described in detail, it will be understood that many modifications will occur to those skilled in the art. It is intended to cover all such modifications that fall within the scope of the appended claims.

What is claimed is—

1. A lath support comprising a member having opposite end portions shaped to embrace spaced laths, and means struck out

from said member intermediate of said end portions for holding an intermediate lath, said member having an intermediate portion shaped for slidable holding engagement with an outlet box supporting bar. 70

2. A lath support comprising a member having means shaped to have sliding holding engagement with an outlet box supporting bar and having end portions shaped to embrace spaced laths, an intermediate portion of said member being provided with a hook-shaped projection for holding an intermediate lath disposed between said spaced laths. 75

3. In combination, an outlet box supporting bar and a sheet metal member slidably supported by said bar, said sheet metal member having a base portion and a portion struck from said base portion intermediate of the length thereof for embracing said bar, said sheet metal member having ears struck therefrom adjacent to the extremities thereof, each of said ears having an end portion lying in a plane substantially parallel to said base portion and forming with said base portion an open-ended slot, said sheet metal member being shaped intermediate of its length to receive and support a lath. 80

4. In combination, an outlet box support bar, a sheet metal member slidably supported by said bar, said sheet metal member having ears struck therefrom having end portions each lying in a plane substantially parallel to said base portion and spaced from said base portion a sufficient distance to receive a lath, said ears extending in a direction transverse to said bar and providing with said base portion open-ended slots opening in opposite directions toward the ends of said member, said sheet metal member being provided with an ear intermediate of said first-mentioned 100 ears adapted to embrace a lath. 105

5. In combination, adjacent studs, a metal bar connected to said studs, spaced laths, each connected to said studs, laths intermediate of said spaced laths, said intermediate laths having end portions disposed between said studs, and means for holding said ends of said intermediate laths, said means comprising a metal member having embracing relationship with said spaced laths and having portions for receiving and holding said ends of said intermediate laths, said member also having a portion having sliding relationship with said bar. 110 115

6. In combination, adjacent joists, spaced laths each connected to said joists, a lath intermediate of said spaced laths, said intermediate lath having an intermediate portion disposed between said joists, an outlet box supporting bar secured to said joists between said spaced laths, and a metal member for holding said end portion of said intermediate lath, said metal member being shaped intermediate of its ends to receive said intermedi- 120 125 130

ate lath and having a struck out portion for slidably receiving said bar, said metal member being also provided with ears adjacent to its extremities for embracing said spaced laths.

- 5 7. In combination, adjacent joists, spaced laths each connected to said joists, a lath intermediate of said spaced laths, said intermediate lath having an end portion disposed between said joists, and means for holding said end portion of said intermediate lath, said means comprising a metal member having end portions shaped to embrace said spaced laths, said metal member being shaped
10 10 intermediate of its length to provide a slot for receiving said intermediate lath, said metal member also being shaped intermediate of its length to embrace an outlet box supporting bar.
- 15 8. In combination, adjacent joists, a metal outlet box supporting bar connected to said joists, spaced laths each connected to said joists, a pair of laths intermediate of said spaced laths, said intermediate laths having end portions disposed between said joists, and means for holding said end portions of said intermediate laths, said means comprising a metal member having ears struck therefrom providing open-ended slots for receiving
20 25 said end portions of said intermediate laths, said member also having struck out portions having holding engagement with said bar and having end portions embracing said spaced laths.
- 30 35 Signed at Chicago, Illinois, this 12th day of October, 1925.

ERNST G. APPLETON.
